UNITED STATES PATENT OFFICE.

ALBERT J. SNOW, OF LOS ANGELES, CALIFORNIA.

EXPANSIBLE DRILL-BIT.

1,095,475.

Specification of Letters Patent.

Patented May 5, 1914.

Application filed July 23, 1913. Serial No. 780,655.

To all whom it may concern:

Be it known that I, ALBERT J. SNOW, a citizen of the United States, residing at Los Angeles, in the county of Los Angeles and State of California, have invented new and useful Improvements in Expansible Drill-Bits, of which the following is a specification.

This invention relates to an expandible rotary bit.

The object of the present invention is to provide a simple, substantial and easily operated rotary bit, which is so constructed that the cutting tools will be automatically opened out into cutting position when projected beyond the end or string of the well casing. It thus becomes possible to cut a sufficiently large hole below the casing to permit the old casing to be lowered or a new string to be inserted without undue surface friction.

Another object of the present invention is to provide a series of fluid conducting passages, so positioned as to deliver fluid at or near the cutting edges, thereby greatly increasing the cutting power of the tools by continuously removing the cuttings and helping to remove the formation while the cutters are at work.

The invention consists of the parts and the construction and combination of parts as hereinafter more fully described and claimed, having reference to the accompanying drawings, in which—

Fig. 1 is a central longitudinal section of the drill body, showing the cutting tools in the expanded or projected position. Fig. 2 is a similar view, showing the tools in contracted position. Fig. 3 is a section of a well showing the position of the expandible rotary drill with relation to the casing. Fig. 4 is a section on line X—X, Fig. 1. Fig. 5 is a section on line V—V, Fig. 1. Fig. 6 is a perspective view, partly in section and broken away, showing the shape of the cutting tool guide slots.

Where a string of casing has been landed and it is necessary to have a larger hole below than the inside diameter of the casing passed through, or where it is desired to carry a string of casing to a greater depth, it is necessary to have a larger hole than the outside of the casing in order to get clearance and overcome friction. This has heretofore been accomplished by first drilling below the casing and then enlarging the hole

by inserting an expandible underreamer. The object of the present invention is to provide a rotary bit, which is so constructed that the cutting tools will automatically expand to the desired diameter, when projected through the casing, thus eliminating the use of an underreamer.

Referring to the drawings, A indicates the main drill body, suitably secured, as at 2, to a drill rod or tubing, indicated at 3. Slidably mounted in the drill body is a pair of rods 4 and 5, to the lower ends of which is pivotally secured, as at 6, a pair of cutting tools 4^a and 5^a. The lower end of the drill body is provided with a pair of upwardly extending slots 7 and 8 into which the upper ends 9 and 10 of the cutting tools extend. The upper extensions 9 and 10 of the cutting tools are provided with inclined faces 11 and 12, as indicated in Figs. 1 and 2, and the inner ends of the slots 7 and 8 are similarly inclined for the purpose of guiding and securing the upper projections of the cutting tools when these are positioned in the slots.

By referring to the perspective view, Fig. 6, it will be seen that the drill body is provided with openings 4' and 5' in which the rods 4 and 5 are slidably mounted, and that slots 4^b and 5^b have been provided for the purpose of permitting the pin 6 to project through the rods 4 and 5 and projections 9 and 10, as indicated in Fig. 4. The slots 4^b and 5^b are of sufficient length to allow the extension or expansion of the cutting tools, as indicated in Figs. 1 and 2.

The upper end of the drill body, to which the drill tubing 3 is secured, is provided with a central chamber 13 into which the upper ends of the rods 4 and 5 project. The outer ends of these rods are threaded, as indicated in Figs. 1 and 2, and provided with adjustable nuts 14 and 15 which secure a cross plate 16, between which and the bottom of the chamber 13 a single compression spring 17 is introduced. The single compression spring 17 positioned as here shown and surrounding the upper ends of the rods 4 and 5 will distribute an even upward pull on the rods 4 and 5 and cause the cutting tool 4^a and 5^a to assume the position indicated in Fig. 1.

In operating an expandible rotary bit constructed as here shown, it is desirable to force fluid under pressure, say from fifty to one hundred or more pounds pressure to the

square inch through the drill, depending upon the depth of the hole and the nature of the material being drilled, for the purpose of removing the cuttings of the tools and 5 also for the purpose of removing cavings or other material. With this object in view I have provided a pair of fluid conducting passages 18 and 19 which extend from the annular chamber 13 to the lower end of the 10 drill body as indicated.

In operation, when it is desired to lower the drill through the casing, it is only necessary to project the cutting tools into the position indicated in Fig. 2. This may be 15 accomplished by pulling the cutting tools out from the supporting slots 7 and 8 against the pressure of the spring 17 and inserting the ends of the cutting tools into the casing. In some instances a wire may be tied around 20 the outer ends of the cutting tools to hold these in the extended contracted position until the tool has been lowered. This will be quickly cut through the moment the bit is rotated at the lower end of the well, and 25 the tools are immediately allowed to expand and assume their normal position, indicated in Fig. 1, being expanded and retracted into the guide slots 7 and 8 by the action of the spring 17 and connected rods 4 and 5. The 30 upper projections 9 and 10 contacting with the inclined faces of the slots 7 and 8 will force the tools into the expanded position. The outer shoulders 21 extending through the slots 7 and 8 will similarly engage with 35 the end of the casing and force the bits into the contracted position shown in Fig. 2, when the drill is lifted, thus allowing the drill to be removed at any time.

In drilling a hole with a rotary drill rig, 40 water is used as a wash and is forced down through the hollow drill tubing 3 into the chamber 13 by hydraulic force. From here the water passes through the passages 18 and 45 19 and is projected through the lower openings at a point just ahead of the cutting edges of the tools. The projected fluid under high pressure will not only help to cut and soften the formation but will also carry the cuttings to the surface.

50 An expandible rotary bit constructed as here shown is simple and substantial in construction and reliable in its actions. Practically any desired diameter may be secured by increasing or decreasing the flare of the 55 cutting tools, and by drilling and enlarging the hole in one operation considerable time

and expense are saved, thus reducing the cost of operation and the efficiency of the tool.

The materials and finish of the several parts of the apparatus are such as experience and judgment of the manufacturer may dictate.

Having thus described my invention, what I claim and desire to secure by Letters Patent is—

1. In combination with a main body having a pair of spaced longitudinal openings and also having slots which extend from said openings toward the center of the body, said body also having a pair of slots which are located between and communicate with the first named slots, a pair of rods slideable in said openings, a pair of cutting tools having overlapping upper ends engaged in the second named slots, a pin passed through the overlapping parts of the cutters and having its ends secured to the respective rods, said body having an enlarged chamber into which the upper ends of the rods project, a coil spring surrounding both of the upper ends of the rods and seating at its lower end on the bottom wall of the chamber and means connecting the rods at their extreme upper ends and being engaged from beneath by the upper end of the spring.

2. In combination with a main body having a central recessed portion and a pair of longitudinal openings which are located on opposite sides of the central recessed portion and communicate therewith, a pair of rods slideable in said respective longitudinal openings, a pin connecting the lower ends of said rods, a pair of cutting tools pivotally mounted on said pin and arranged in said recessed portion, and unitary spring means for normally exerting upward tension on both of the rods.

3. In combination with a body having a pair of longitudinal openings, a rod slideable in each of said openings, means connecting the lower ends of said rods, a pair of cutters pivotally mounted on said means, and means to tension said rods to exert upward pull thereon.

In testimony whereof I have hereunto set my hand in the presence of two subscribing witnesses.

ALBERT J. SNOW.
